Primary Examiner — Sandra L Morris(74) Attorney, Agent, or Firm — Harness, Dickey & Pierce, P.L.C.(57) CLAIM

The ornamental design for packaging for snack pack, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a front plan view of a packaging for snack pack embodying our new design, the other surfaces being unornamented.
